Primary Examiner — Marissa J Cash*(74) Attorney, Agent, or Firm* — Rumit Ranjit Kanakia(57) **CLAIM**

The ornamental design for a arc lighter, as shown and described.

DESCRIPTION

FIG. 1 is a front elevational view of a arc lighter showing my new design;
FIG. 2 is a rear elevational view thereof; and
FIG. 3 is a left side view thereof;
FIG. 4 is a right side view thereof;
FIG. 5 is a top plan view thereof;
FIG. 6 is a bottom plan view thereof;
FIG. 7 is a perspective view of a arc lighter showing my new design; and,
FIG. 8 is another perspective view showing the upper part of the arc lighter is bent.
The broken lines in the figures are for the purposes of illustrating portions of the arc lighter, which form no part of the claimed design.
